UNITED STATES PATENT OFFICE.

HERBERT CLOUSTON, OF MOHALL, NORTH DAKOTA.

GRAVITY FUEL-FEEDING DEVICE.

1,022,772.

Specification of Letters Patent. Patented Apr. 9, 1912.

Application filed May 29, 1911. Serial No. 630,125.

To all whom it may concern:

Be it known that I, HERBERT CLOUSTON, a citizen of the United States, residing at Mohall, in the county of Ward and State of 5 North Dakota, have invented certain new and useful Improvements in Gravity Fuel-Feeding Devices; and I do hereby declare the following to be a full, clear, and exact description of the invention, such as will 10 enable others skilled in the art to which it appertains to make and use the same.

My invention has for its object to provide an extremely simple and highly efficient gravity-feed device or stoker adapted for 15 use to automatically feed cut straw, sawdust, cut corn cobs and similar finely divided fuel to stoves and furnaces.

To the above ends, the invention consists of the novel devices and combinations of 20 devices hereinafter described and defined in the claims.

In the accompanying drawings which illustrate the invention, like characters indicate like parts throughout the several 25 views.

Referring to the drawings, Figure 1 is a view in elevation with some parts broken away and with some parts sectioned showing my improved feed device or stoker connected to the fire box of a stove; and Fig. 2 is an enlarged vertical section taken on the line $x^2 x^2$ of Fig. 1.

The numeral 1 indicates the wall of a building and the numeral 2 indicates a 35 heating stove having a suitable fire pot 3, equipped with a suitable grate 4.

The fuel which is to be fed into the fire pot of the stove is placed within a supply hopper 5, preferably constructed of sheet 40 metal and having an inclined bottom 6, that extends from one side nearly to the other of the said hopper and connects with the upper extremity of a feed spout 7, which latter leads downward from the lowermost portion 45 of the hopper and is connected to the fire box of the stove through an opening 8 in one side of the stove. Preferably, the supply hopper 5 will be located outside of the building so that it may be filled without 50 entering the room in which the stove is installed, hence, this feed spout 7 is passed obliquely through the wall 1, substantially as shown in Fig. 1.

The hopper 5 is divided into a multiplicity 55 of vertical compartments a , b , c and d ,

by means of partitions f^1 , f^2 , and f^3 , the upper ends of which are preferably terminated at the top of the hopper and the lower ends of which are, in the order named, cut off at points higher and higher so that they 60 are spaced approximately the same distance from the inclined hopper bottom 6. Preferably, also, the hopper 5 is provided with a detachable cover 9.

The numeral 10 indicates a damper which 65 controls a draft passage located on the side of the stove just below the point of delivery of the spout 7 into the fire pot.

The numeral 11 indicates a pin, or similar 70 device, which may be inserted transversely through the lower portion of the feed spout 7 to hold back the straw or similar fuel when it is not desired that the same should be fed into the stove.

When all of the compartments of the hopper are filled with straw, sawdust or similar fuel, and the pin or hold-back device 11 is removed, the fuel will be gravity fed into the fire box or stove. In as much as the compartment a is located vertically directly 75 over the feed spout 7, the fuel contained therein will have less frictional support 80 than the fuel in the other compartments b , c and d , and hence, the fuel from this compartment a will first be delivered to the

stove before any, or much, of the fuel from 85 any of the other compartments will be delivered into the feed spout 7. The compartment b is not as much off-set from the spout 7 as the compartments c and d , and hence, after the compartment a has been 90

nearly or quite emptied of fuel, the fuel from the compartment b will be fed to the spout 7, and thence, to the stove. Under 95

this arrangement, the one compartment after the other will be emptied of fuel and the compartment which is most remote laterally from the feed spout, or point of discharge from the hopper will be the last to 100 be emptied of fuel. By dividing the hopper into a multiplicity of compartments, and allowing one to empty at a time, the fuel is evenly fed onto the grate. It has been demonstrated, in actual usage, that by removing the partitions from the hopper, the fuel, particularly straw on account of its 105 lightness, will pack at the receiving end of the spout 7. Fuel may be inserted into any of the emptied compartments at any time without interrupting the feeding action. 110

I have found, in practice, that when sawdust for instance, is to be burned, that a supply of air should be delivered into the fire box directly below the point of delivery of the fuel into the fire box. Hence, when sawdust is burned, the draft port or passage 10 should be opened. On the other hand, when straw is to be burned, the port 10 should be closed and the draft should be 10 directly upward through the bottom and central portion of the grate. Of course, a finer grate should be used for sawdust than for straw.

What I claim is:

- 15 1. A fuel feeding device comprising a hopper having an inclined bottom, a feed spout leading downward from the lower portion of the inclined bottom, said hopper having a plurality of substantially vertically disposed partitions, spaced apart to form a series of fuel compartments, laterally at different distances from the said feed spout, the said partitions terminating
- 20

short of the inclined bottom to form an inclined chute leading to the feed spout.

25

2. A fuel feeding device comprising a hopper having an inclined bottom, a feed spout leading downward from the lower portion of the inclined bottom, said hopper having a plurality of substantially vertically disposed partitions, spaced apart to form a series of laterally off set fuel compartments, one of said compartments being located directly over said feed spout and the others thereof being located at different distances 30 from the said feed spout, the said partitions terminating short of the inclined bottom to form an inclined chute leading to the feed spout.

30

35

In testimony whereof I affix my signature 40 in presence of two witnesses.

HERBERT CLOUSTON.
